UNITED STATES PATENT OFFICE.

RUFUS E. BOSCHERT, OF SYRACUSE, NEW YORK.

PRESSURE-PLATE FOR APPLE-GRINDERS.

SPECIFICATION forming part of Letters Patent No. 247,007, dated September 13, 1881.

Application filed August 11, 1881. (No model.)

To all whom it may concern:

Be it known that I, RUFUS E. BOSCHERT, of Syracuse, in the county of Onondaga, in the State of New York, have invented new and useful Improvements in Pressure-Plates for Apple-Grinders, of which the following, taken in connection with the accompanying drawings, is a full, clear, and exact description.

This invention relates to the vibratory pressure-plates used as a safety-feed to rotary cutting or grinding cylinders, and has, more particularly, reference to the pressure-plate employed in connection with the apple-grinder shown in Patent No. 225,456.

15 In the use of the said machine it has been found that, owing to the rigidity between the pressure-plate and its weighted lever, the sudden check of the vibration of said parts produced such concussions as to impair the stability of the machine, and in some instances break the pressure-plate or its connections; and since the said plate and its lever were made in one piece, the breakage of either of them destroyed the use of both.

25 It is to obviate these defects that my present invention has for its object; and to that end it consists in providing the pressure-plate with a rearward-projecting shoulder, upon which is secured a rubber or other elastic cushion, and pivoting the weighted lever independently of the pressure-plate, and bringing it to bear on the cushioned shoulder thereof, all as hereinafter more fully described.

In the accompanying drawings, Figure 1 is 35 a side view of my invention, and Fig. 2 is a vertical section taken directly at the side of the weighted lever.

Similar letters of reference indicate corresponding parts.

40 B represents the grinding-cylinder, journaled horizontally on a frame, A, which is extended the length of the cylinder and across the ends thereof.

45 From the frame A, at the ends of the cylinder, rise standards D, to the upper ends of which is connected a rod, c, extended from standard to standard.

C denotes one of a series of pressure-plates, which are usually arranged side by side along 50 the face of the cylinder and suspended from the rod c, so as to allow them to vibrate to

and from the cylinder. The lower end of the respective pressure-plates is normally nearest the cylinder, and its proximity to the same is limited by a check-rod, r, which is extended 55 rearward from the lower end of the pressure-plate, and has on its extremity an adjusting-nut, n, engaging a rearwardly-facing shoulder, o, on the frame A, and thus checking the forward swinging of the pressure-plate.

60 The upper portion of the pressure-plate C, I provide with a rearward-projecting shoulder, a, and along the top thereof is a slot, e, in which lies a lever, l, which is pivoted at one end on the rod c independently of the pressure-plate, and carries at its free end a weight, w, adapted to be set at a greater or less distance from the fulcrum of the lever, according to the pressure desired on the pressure-plate C, said pressure being transmitted to the plate 65 C by the bearing of the lever l on the shoulder a.

In the operation of the machine the pressure-plate C presses the substance to be ground against the face of the grinding-cylinder B, 70 and thus subjects said substance to the knives or cutters on the cylinder.

In case a stone or other hard foreign substance happens to enter between the pressure-plate and grinding-cylinder, the pressure-plate 75 yields and swings back to allow the said substance to escape at the base of the pressure-plate. So soon as the space between the pressure-plate and cylinder is cleared the pressure of the weighted lever l on the pressure-plate C 80 restores the latter to its normal position, which is determined by the nut n on the end of the check-rod r encountering the shoulder o on the frame A, as before described.

To obviate the jars incident to the sudden 85 check in the movement of the pressure-plate, I interpose between the lever l and its bearing on the shoulder a of the pressure-plate a rubber or other elastic pad or cushion, b, which is secured in a socket in the shoulder a, as 90 shown in Fig. 2 of the drawings, said cushion receiving the pressure of the descending lever l, and thus preventing the jars, as aforesaid.

Having thus fully described my invention, 95 I claim—

1. In combination with the grinding-cylin-

der B, the suspended pressure-plate C, provided with the shoulder *a*, and the lever *l*, pivoted independently of the pressure-plate and supported at its free end by the shoulder *a*, substantially as set forth.

2. In combination with the rotary cylinder B, the vibratory pressure-plate C, having the shoulder *a*, provided with the cushion *b*, and the lever *l*, pivoted independently of the pressure-plate and resting on the cushion *b* thereof, substantially as shown and described, for the purpose set forth.

In testimony whereof I have hereunto signed my name and affixed my seal, in the presence of two attesting witnesses, at Syracuse, in the county of Onondaga, in the State of New York, this 8th day of August, 1881.

RUFUS E. BOSCHERT. [L. S.]
